UNITED STATES PATENT OFFICE

ARTHUR WILLIAM RASMUSSON, OF LEAD, SOUTH DAKOTA

DESIGN FOR A COMBINATION STAND FOR SMOKERS' ARTICLES

Application filed September 5, 1931. Serial No. 41,033. Term of patent 3½ years.

To all whom it may concern:

Be it known that I, ARTHUR W. RASMUSSON, a citizen of the United States of America, residing at Lead, in the county of Lawrence and State of South Dakota, have invented a new, original, and ornamental Design for a Combination Stand for Smokers' Articles, of which the following is a specification, reference being had to the accompanying drawings, forming part thereof.

Figure 1 is a perspective view of my design for a combination stand for smokers' articles,

Figure 2 is a front elevational view thereof, Figure 3 is a rear elevational view, and; Figure 4 is a top plan view.

I claim:

The ornamental design for a combination stand for smokers' articles as shown.

ARTHUR WILLIAM RASMUSSON.
